UNITED STATES PATENT OFFICE.

CARL JOHAN LUNDSTROM, OF LITTLE FALLS, NEW YORK, ASSIGNOR TO
D. H. BURRELL & CO., OF SAME PLACE.

CENTRIFUGAL SEPARATOR.

SPECIFICATION forming part of Letters Patent No. 543,213, dated July 23, 1895.

Original application filed January 24, 1893, Serial No. 459,533. Divided and this application filed November 28, 1894. Serial No. 530,227. (No model.) Patented in Canada July 6, 1893, No. 43,500.

To all whom it may concern:

Be it known that I, CARL JOHAN LUNDSTROM, a subject of the King of Sweden and Norway, residing at Little Falls, in the county 5 of Herkimer and State of New York, have invented a new and useful Improvement in Centrifugal Separators, (for which I have obtained Letters Patent of Canada, No. 43,500, dated July 6, 1893,) of which the following is 10 a specification.

This invention relates to that class of centrifugal separators which are employed for separating a compound liquid or an emulsion into its constituent liquids of different densities, particularly for separating full milk into 15 cream and skim-milk.

The space in the drum or bowl which is occupied by the liquid is often provided with a division device, which separates the liquid 20 into distinct bodies and which increases the separating capacity of the bowl. In Letters Patent No. 514,156, granted to me February 6, 1894, upon an application filed January 24, 1893, Serial No. 459,533, a single hollow separating-cone is shown and described in the liquid 25 space of the bowl for this purpose.

The improvement which forms the subject-matter of this application has the object to further increase the separating capacity of 30 this separating device and the closeness of the separation. This improvement formed part of the subject-matter which was disclosed and claimed in said original application for Letters Patent and was removed therefrom 35 and forms now the subject-matter of this divisional application.

In the accompanying drawings, Figure 1 is a sectional elevation of the bowl of a centrifugal creamer provided with my improvements.

40 Fig. 2 is a horizontal section in line $\alpha\alpha$, Fig. 1. Figs. 3 and 4 show slightly-modified forms of the invention.

Like letters of reference refer to like parts in the several figures.

45 A represents the stationary curb or surrounding case, which is of ordinary construction and supported in the usual way on a suitable frame.

B is the spindle, which is journaled near

its upper end in the usual bearing b in the 50 bottom of the curb.

C represents the bottom, and C' the peripheral wall of the bowl.

D represents the feed-cup arranged centrally on the bottom of the bowl and provided 55 with one or more discharge-pipes d , through which the full milk passes from the feed-cup into the liquid space of the bowl. The outer ends of these pipes are preferably arranged so far from the axis of the bowl that the full 60 milk enters the liquid space outside of the cream-wall.

E represents the cover of the bowl, which is removably secured to the peripheral wall in any usual way and which tapers upwardly 65 to a contracted neck E'. This cover is provided on its under side with the usual skim-milk discharge-pipes f and in its contracted neck with the cream-outlet f' .

G G' represent the superposed receptacles 70 for the separated skim-milk and cream resting upon the curb.

H represents the milk-receptacle from which the full milk passes through a discharge-pipe h into a tubular stem or feed-pipe I, arranged axially in the bowl, and thence 75 into the feed-cup D.

The construction of the above-described parts may be varied in many respects, and these parts may be constructed and arranged 80 in any other well-known or suitable manner.

K represents a hollow separating-cone which is arranged in the liquid-space of the bowl and which rests upon the bottom of the bowl at or near the peripheral wall thereof, 85 and extends obliquely upwardly and inwardly from the bottom toward the cream-outlet and terminates with its contracted end in the vicinity of the cream-outlet.

K' K² represent supplemental concentric 90 separating-cones of similar construction, arranged within the cone K, and successively smaller in size toward the axis of the bowl. The full milk enters the liquid-space within the inner cone K² and is there subjected to 95 centrifugal action, whereby the cream-globules are crowded toward the axis of rotation while the globules of blue milk or skim-milk

are driven outwardly. The cream-globules accumulating in the inner layer of the body of liquid are moved upwardly toward the cream-outlet by the incoming supply of milk at the bottom of the bowl, while the particles of blue milk reach in their outward course the inner surface of the cone K^2 and move downwardly along the latter under the action of centrifugal force and finally pass around the lower edge of this cone into the lower portion of the space between the cones K^2 and K' . The cones are constructed of tin or other suitable material and rest loosely on the bottom of the bowl, so that the centrifugal force can drive the liquid past the lower edges of the cones. In the space between the inner cones K^2 and K' the milk is subjected to a similar separating action, the cream-globules moving inwardly and upwardly and joining at the upper end of the innermost cone the cream separated in the latter, while the blue milk moves outwardly and downwardly and passes around the lower edge of the cone K' into the space between the cones K' and K . In this space a similar separation is effected, the cream passing inwardly and upwardly and joining the cream separated in the previous separations, while the blue milk escapes past the lower edge of the outer cone K into the space between the latter and the peripheral wall of the bowl, where the final separation is effected. The cream separated in this space passes inwardly and upwardly and joins the cream from the previous separations in passing to the cream-outlet while the skim-milk escapes through the skim-milk pipes. The full milk is by this means subjected in an extremely simple manner to several successive separations, whereby the cream particles are completely separated from the blue or skim milk.

Each cone is preferably provided on its outer side with several radial blades $m m' m^2$, whereby the cones are held apart in their proper position in the bowl and whereby the liquid is prevented from shifting its position circumferentially and is compelled to rotate

with the bowl. The innermost cone may also be provided with internal blades n for the last-named purpose.

When it is desired to clean the bowl and cones the cover of the bowl is removed and the cones are taken out.

The cones may be made of various forms—for instance, with parallel sides and tapering throughout their height, as represented in Fig. 1, or of different taper and upwardly converging, as represented in Fig. 3, or in their lower portions cylindrical, as represented in Fig. 4.

I claim as my invention—

1. The combination with the separating bowl, having an inlet for the full milk and discharges for the separated cream and skim milk, of an outer separating cone extending diagonally through the liquid space from the bottom of the bowl toward the cream outlet, and a preliminary separating cone of smaller diameter arranged within the outer cone, substantially as set forth.

2. The combination with the separating bowl having an inlet for the full milk and discharges for the separated cream and skim milk, of hollow separating cones of different diameters arranged loosely upon the bottom of the bowl around the inlet for the full milk and extending diagonally through the liquid space of the bowl toward the cream outlet, whereby the milk is separated first within the innermost cone and then successively in the surrounding spaces, the separated cream passing directly from the small upper end of each cone toward the cream outlet, while the skim milk of the first separation passes past the lower end of the innermost cone and successively through the separating spaces surrounding the latter, substantially as set forth.

Witness my hand this 12th day of November, 1894.

CARL JOHAN LUNDSTROM.
